PUMP

Herbert Allen, Houston, Tex., assignor, by mesne assignments, to Stephens Pump Company, Round Rock, Tex., a corporation of Delaware

Application May 14, 1934, Serial No. 725,570

6 Claims. (Cl. 103—220)

This invention relates generally to pumps and specifically to strainers for the suction manifolds thereof.

It has for its general object the provision of a new and improved strainer that will efficiently prevent the entrance into the pump of foreign matter, and that may readily be removed, cleaned and replaced. A further object of this invention is to provide a new and improved inlet manifold such that the straining action in it is more uniform and less localized.

Specific objects will hereinafter appear.

The preferred embodiment of the invention is illustrated by the accompanying drawing wherein in Fig. 1 is a fragmentary partly sectional elevation of a pump in which the strainer may be effectively used; and Fig. 2, a detail partly sectional view of the suction manifold and strainer assembly.

The drawing illustrates one of the various pumps with which the present invention may be effectively used. This pump is of the type fully described by the patent to Stephens No. 1,848,441, and includes a pair of axially aligned and spaced barrels 2 and 3. The barrel 3 has pump inlet and outlet means 4 and 5, respectively and the barrel 2 has corresponding pump inlet and outlet means. Communicating with the barrel 3 through its inlet means is a pump inlet passageway 7, and communicating with the barrel 2 through its inlet means is the pump inlet passageway 6. The numeral 8 indicates a piston which is reciprocated to actuate pumping fluid confined within hollow expandable members in each of the barrels such as that indicated at 9 in the barrel 3 to effect the expansion and contraction of said members to draw pumped fluid through the pump inlet passageways 6 and 7 into the barrels, and to expel it from the barrels through the pump outlet means of the barrels. The inlet and outlet means (such as 4 and 5) include valves, and the pump operates in the manner set forth in the said patent to Stephens 1,848,441.

Referring now to the present invention, the pump includes a suction manifold 10 extending substantially transversely of the barrels 2 and 3, and having in its opposite sides staggered manifold outlet ports 11 and 12 which may be connected to the pump inlet passageways 6 and 7, respectively, by means of the flanges 13 and 14. One end of the suction manifold 10 may have thereon a cover 15, and the other end may be connected by means of flanges 16 and 17 to an entrance pipe 18.

The body of the suction manifold 10 comprises substantially an elongated cylinder, and within the manifold 10 is placed a screen comprising a substantially cylindrical perforated pipe concentric and coextensive therewith and radially spaced therefrom. 5

The pumped fluid enters the strainer 19 through the entrance pipe 18 and passes through the perforations into the space between the strainer 19 and manifold 10, and then through the manifold outlet ports 11 and 12 into the pump inlet passageways 6 and 7 and finally into the barrels 2 and 3. As a result of staggering these inlets the fluid leaves the inlet manifold at two different points spaced longitudinally thereof, 15 thus facilitating a more even flow of fluid through the manifold and allowing the fluid to be strained over a more extensive area of the screen, thus avoiding a single localized zone of screening action. This also avoids the accumulation of 20 screened matter at a single point in the manifold and materially lessens the possibility of a stoppage.

The foreign matter or trash is trapped within the screen 19, and after the cover 15 has been 25 removed the screen 19 may be pulled out of the manifold 10 and the foreign matter or trash removed therefrom, after which the screen and cover may readily be replaced.

It will be obvious that the foreign matter or 30 trash will be removed from the pumped fluid without interference with the free movement of the pumped fluid into the barrels, and that the screen may be quickly and easily cleaned.

Various advantages other than the advantages 35 referred to hereinabove will be apparent to those skilled in the art. The invention is not limited to the preferred embodiment herein disclosed. Various changes may be made within the scope of the following claims. 40

I claim:

1. A pump having a suction manifold, said manifold having an elongated substantially cylindrical body with staggered manifold outlet ports between its ends and an entrance opening 45 at one end; a strainer in said manifold having a substantially cylindrical body concentric and coextensive with and radially spaced from the body of said manifold, perforated, and communicating with said entrance opening; said manifold having on one end a removable cover, and said strainer being insertable in and removable thru said end when said cover is removed. 50

2. A pump having a suction manifold, said manifold having an elongated substantially cy- 55

lindrical body with staggered manifold outlet ports between its ends and an entrance opening at one end; a strainer in said manifold, said strainer having a substantially cylindrical body concentric and coextensive with and radially spaced from the body of said manifold, perforated, and communicating with said entrance opening.

5. A pump having a pair of axially aligned spaced barrels each having inlet and outlet means; an elongated suction manifold extending substantially transversely of said barrels; staggered manifold outlets an inlet passageway on each side of said suction manifold, extending upwardly to one of said barrels and connected to one of said manifold outlets; and a strainer within and co-extensive with said manifold.

10. A pump having a pair of axially aligned spaced barrels; an elongated suction manifold extending substantially transversely of said barrels; an inlet passageway on each side of said suction manifold and extending upwardly to one of said barrels; and a strainer in said manifold.

15. A pump having a plurality of longitudinally aligned barrels, each of said barrels having inlet

and outlet means, a main inlet pipe extending transversely of said barrels and having a plurality of outlets in staggered relation with respect to its length, a foraminous strainer substantially cylindrical in form interiorally of said main inlet pipe and in spaced relation to the interior walls thereof, and means connecting the outlets in said main inlet pipe to the inlet means of said barrels.

20. A pump having a pair of axially aligned barrels; a suction manifold having an elongated substantially cylindrical body extending substantially transversely of said barrels having staggered manifold outlet ports between its ends communicating with said barrels; an entrance opening at one end of said manifold; a strainer in said manifold having a substantially cylindrical body, perforated, concentric and coextensive with and radially spaced from the body of said manifold, and communicating with said entrance opening; a removable cover on one end of said manifold; and said strainer being insertable in and removable from said end when said cover is removed.

HERBERT ALLEN.
